[57] ABSTRACT

A device for containing an alkali metal chloride candle which is burned to produce oxygen. The device includes a generally cylindrical housing having an end cap which closes the interior of the housing. A tray for holding the candle is secured to the end cap and is withdrawn from the housing when the end cap is removed. A filter is mounted on the end cap for easy replacement.

FIG-3

FIG-1

FIG-2

OXYGEN GENERATOR

This invention relates to a device for containing an alkali metal chlorate candle which candle is burned to produce oxygen for use in life support systems, oxy-fuel torches, and other such applications.

The provision of oxygen for use in life support systems, oxy-fuel torches, and the like has been made by utilizing cylinders containing oxygen under pressure, such cylinders being quite heavy, bulky, and not readily adaptable with highly mobile or portable systems. The provision of oxygen for such applications has also been made by the more desirable use of alkali metal chlorate candles which, when burned, produce oxygen. The latter more readily lends itself to use with light weight portable systems of the type described due to the light weight of the chlorate candles.

When a chlorate candle is burned to produce oxygen the candle must be contained in some sort of housing so that burning the candle is rendered safe, and so that the oxygen produced can be readily filtered and dispensed. Ideally the housing in which the candle is burned should be relatively inexpensive to make, of relatively simple construction, and yet sturdy enough to contain the candle and its pressurized gaseous product. The housing should also be amenable to easy loading with new candles and unloading of consumed candle ash. Provision should also be made to filter the produced oxygen, with the filter being easily replaceable.

The prior art candle-holding oxygen generators have, for the most part, been of relatively bulky construction, thus failing to maximize on one of the primary attributes of chlorate candles, e.g. their relatively small size. The prior art which most closely makes use of the size of the chlorate candles to produce a light weight, portable oxygen generator is typified by U.S. Pat. No. 2,775,511, issued Dec. 25, 1956 to R. Geffroy et al.; and U.S. Pat. No. 3,253,787, issued May 31, 1966 to K. E. Stutzman.

The oxygen generator of this invention is highly portable, provides for easy insertion and removal of fresh and consumed candles, and readily changeable filtering. The generator includes a generally tubular housing member which is preferably formed of extruded aluminum, or other highly efficient heat-conducting metal, and which preferably includes longitudinally extending integral fins externally to readily dissipate heat produced when the chlorate candles are burned. A plug with a blow-out bladder closes one end of the housing, and a cap closes the other end of the housing. The cap is preferably press fitted into the housing bore and held in place by a rubber gasket or collar so as to be manually removable from the housing. A tray is mounted on the cap and extends therefrom into the housing, the candle being positioned on the tray for burning. The cap is also provided with a dispensing valve assembly which opens into an external fitting adapted to be connected to a hose through which the oxygen passes. A preferably conical filter is frictionally mounted on the cap adjacent the tray so as to be readily removable from the housing for handy changing of the filter when the latter becomes clogged.

It is, therefore, an object of this invention to provide an oxygen generator of the type utilizing a chlorate candle which is burned to produce oxygen.

It is a further object of this invention to provide an oxygen generator of the character described wherein

provision is made for handily loading and unloading fresh and used candles respectively from a housing.

It is yet another object of this invention to provide an oxygen generator of the character described having provision for readily changing the filter when the latter becomes clogged.

It is an additional object of this invention to provide an oxygen generator of the character described which is inexpensive and of simple construction.

These and other objects and advantages of the invention will become more readily apparent from the following detailed description of a preferred embodiment of the invention taken in conjunction with the accompanying drawings, in which:

15 FIG. 1 is a perspective view of a preferred embodiment of the oxygen generator of this invention used in association with a torch in an oxy-propane torch assembly;

20 FIG. 2 is a longitudinal cross-sectional view of the oxygen generator of FIG. 1 showing the internal construction thereof; and

25 FIG. 3 is a fragmentary sectional view of a pressure relief valve on the generator showing the relief valve being blown open to relieve excess pressure within the generator.

Referring now to the drawings, the oxygen generator, indicated generally by the numeral 2 is shown used as part of a portable oxy-propane torch. The torch includes a conventional torch head to which are connected flexible conduits 6 and 8 which lead to the oxygen generator 2 and a propane fuel tank 10 respectively. A conventional mixing chamber is disposed in the torch head 4 for intermixing the oxygen and propane.

35 The oxygen generator 2 includes a generally tubular housing 12 preferably formed of extruded aluminum, or some other material having efficient heat conducting properties. The housing 12 is formed with external longitudinally extending ribs 14 which serve to dissipate heat from the inside of the housing produced when a chlorate candle is burned therein. The bottom or rearward end of the housing 12 is closed by a cap 16 having a bore 15 which opens into a smaller bore 17 communicating with the interior of the housing 12. A hollow plug 20 is positioned in the bore 15, the plug having a through passage 19. The plug 20 serves to retain a rubber diaphragm 18 in place within the bore 15 to seal the plug bore 19 at lower pressures. In the event that fluid pressure within the housing builds to an undesirable level, the diaphragm 18 will collapse and be dislodged in the bore 19 to open the latter thus venting the housing interior to the atmosphere, as shown in FIG. 3.

40 A cap 22, which may be formed of rigid plastic material, closes off the front or top end of the housing 12. The cap 22 has a neck 24 on which is mounted a rubber collar 26. The collar 26 provides a sealed friction fit with a bore 28 in the housing 12. The cap 22 includes an internal transverse wall 30 having a bore 32 in which is mounted a fitting 34. The fitting 34 includes a through passage 36 and a stem 38 on which is mounted the hose 6. The remainder of the fitting 34 is externally threaded to receive a nut 40 and a check valve housing 42 which combine to hold the fitting 34 tightly in the bore 32. A ball 44 is loosely mounted in the valve housing 42 and cooperates with a valve seat 46 to form a one way check valve which prevents gas from flowing backward from the hose 6 into the housing 12, but per-

mits gas to flow forward from the housing 12 to the hose 6.

A conical filtering member 48 is mounted on the valve housing 42 and extends into the interior of the housing 12. The conical shape of the filter 48 provides increased filtering area and thus increased filter life when compared to conventional filter pads. The conical shape of the filter 48 also permits the filter to be pressed down over the valve housing 42 thus connecting the filter 48 to the cap 22.

An elongated tray 50 is disposed in the housing 12 and carries the chlorate candle C (shown in phantom). The tray 50 includes a bottom wall 52 on which the candle C rests, upturned side walls 54, and upturned rearward end wall 56, and an upturned forward end wall 58 having an opening 60. The tray 50 is connected to the cap 22 by passing the fitting 34 through the opening 60 and trapping the tray end wall 58 between the valve housing 42 and the inside surface 62 of the cap transverse wall 30.

The oxygen generator operates in the following manner. Assuming that a fresh candle is to be placed in the housing 12, the cap 22 is manually pulled free of the housing 12, thus withdrawing the tray 50 from the housing 12. A candle is then placed on the tray 50 and ignited with a match, or the like. The tray 50 is then reinserted into the housing 12 and the rubber collar 26 is pushed firmly into the housing counterbore 28 to affix the cap 22 to the housing 12. As the candle C burns, oxygen is produced which raises the gas pressure within the sealed housing 12. The oxygen flows through the filter 48, the valve housing 42 and the passage 36 into the hose 6. The oxygen then passes through the hose 6 to be used for whatever purpose the generator is put to. To remove a consumed candle from the generator, one need merely pull the cap 22 away from the housing 12 so as to withdraw the tray 50 from the housing interior. The consumed candle is then merely dumped from the tray and replaced with a fresh candle. To replace the filter 48, the cap 22 is pulled away from the housing 12 and the filter 48 is pulled off of the valve housing 42 and a new filter is pushed onto the valve housing.

It will be readily apparent to those skilled in the art

that the oxygen generator of this invention is of simplified construction and yet readily provides for improved performance, portability and servicing. The candles are easily inserted into and withdrawn from the generator by providing a candle tray which is secured to the closure cap of the generator. The valve housing serves several purposes in addition to valving oxygen from the generator, particularly it secures the tray to the cap and provides means for mounting the filter to the cap. Further, the hollow conical shape of the filter provides improved filtering capacity and an inherent facility for mounting the filter to the valve housing.

Since many changes and variations of the disclosed embodiment of the invention may be made without departing from the inventive concept, it is not intended to limit the invention otherwise than as required by the appended claims.

What is claimed is:

1. An oxygen generating device for use with a combustible oxygen-producing candle, said device comprising:
  - a. a generally tubular housing having a hollow interior and an open end portion;
  - b. a cap removably secured to said open end portion of said housing to close the latter;
  - c. fitting means providing a fluid passage through said cap to allow oxygen gas to exit from said housing interior;
  - d. check valve means including a valve housing secured to said fitting means for controlling oxygen gas flow from said housing;
  - e. a tray disposed in said housing interior for supporting a candle during combustion thereof, said tray including a portion thereof sandwiched between said cap and said valve housing whereby said tray is secured to said cap and removed from said housing interior when said cap is withdrawn from said open end portion of said housing; and
  - f. a hollow filter member having an open basal portion which is telescoped over and removably mounted on said valve housing to filter oxygen gas flowing from said housing.
